UNITED STATES PATENT OFFICE

ALEXANDER B. DICKERSON, OF NEWARK, NEW JERSEY

STOCKING PROTECTOR

Application filed August 7, 1928. Serial No. 297,979.

This invention relates to an improved protector to be used by women or men in rainy or slushy weather in order to protect the stockings from water and grease

5 The invention is a protector that is waterproof but looks like a silk stocking in texture; is extended down over the foot or shoe as it is preferably used over the shoe; is very thin and can be folded or crumpled within the 10 hand and is thus adapted for removal and carrying in a hand bag; and is shapely as it may have bands to cause it to adhere closely to the leg in addition to a thin elastic waterproof inside or outside face, as rubberized 15 cloth.

The invention is illustrated in the accompanying drawings in which Figure 1 is a perspective view showing my improved protector in place. Figure 2 is an enlarged section 20 on line 2-2 in Figure 1 and Figure 3 is a detail section to show in exaggerated form, the cross-sectional appearance of the fabric.

The protector is made of rubberized silk, imitation silk, rayon, celanese or cotton or entirely of rubber and is formed into a portion 25 10 for the leg and a portion 11 which extends down over the shoe. The device thus covers the silk stocking and extends down over the shoe to be worn over or under rubbers when 30 rubbers are worn. It protects these parts from being spattered with mud and water as the cloth 12 of which the protector is made has a lining or inner or outer surface 13 applied as in any form of rubberized fabric.

35 The protector is usually made to provide a neat fit and is as good in appearance as a silk stocking. It can be made to insure a snug fit by elastic bands or tie straps, one being shown at 14, just below the knee, and one at 15, just 40 above the ankle.

The bottom part of the protector is held down by a strap 16 which passes under the instep and may be fastened by a buckle or other suitable means or permanently attached 45 as an integral part of the stocking.

To insure a snug fit at the instep the device may be provided with a frame and I show a wire frame 17 extending from the sides of the bottom and forming loops over the instep and 50 over the heel as one form of frame to be used.

It may be secured in place by stitching, cement or any other manner.

The protector can be quickly removed when going indoors and the stockings underneath 55 are free from spots. The device can be folded to a small mass on account of the thin materials used and can be easily placed in a small bag or ladies' hand bag.

Various modifications can be made in the article without departing from the scope of 60 the invention.

I claim:—

A stocking protector comprising a continuous thin elastic fabric to fit the leg and to be supported over a stocking by its own elasticity, said fabric being waterproof and a 65 wire member incorporated in the foot portion of the protector, said member extending along both sides of the foot and having loops to extend over the instep and around the 70 back of foot above the heel.

In testimony whereof I affix my signature.

ALEXANDER B. DICKERSON.
